Primary Examiner — Catherine S Posthauer(74) *Attorney, Agent, or Firm* — Womble Bond Dickinson (US) LLP(57) **CLAIM**

The ornamental design for a lid, as shown and described.

DESCRIPTION

FIG. 1 is a perspective view of a lid showing my new design and in a closed configuration.

FIG. 2 is a front elevation view of the lid of FIG. 1.

FIG. 3 is a rear elevation view of the lid of FIG. 1.

FIG. 4 is a right elevation view of the lid of FIG. 1.

FIG. 5 is a left elevation view of the lid of FIG. 1.

FIG. 6 is a top plan view of the lid of FIG. 1.

FIG. 7 is a bottom plan view of the lid of FIG. 1; and, FIG. 8 is a perspective view of the lid of FIG. 1 in an open configuration.

The broken lines are shown for the purpose of illustrating parts of the article that form no part of the claimed design.
